Geo. W. Oliver.

UNITED STATES PATENT OFFICE.

GEORGE W. OLIVER, OF CHATTANOOGA, TENNESSEE.

ADJUSTABLE PITCH-BOARD.

SPECIFICATION forming part of Letters Patent No. 378,069, dated February 14, 1883.

Application filed October 14, 1885. Serial No. 179,883. (No model.)

To all whom it may concern:

Be it known that I, GEORGE W. OLIVER, a citizen of the United States, residing at Chattanooga, in the county of Hamilton and State 5 of Tennessee, have invented certain new and useful Improvements in Adjustable Pitch-Boards, of which the following is a description.

This invention has relation to that class of 10 measuring-instruments commonly known as "pitch-boards," used by carpenters and joiners to lay off miters, and more particularly by stair-builders to lay off the risers and treads of stairs.

15 The object of the invention is to provide an instrument for the purpose mentioned which can be adjusted and set to serve as a guide for laying off work wherein steps of different treads and risers and miters of different angles are 20 involved.

Referring to the drawings, Figure 1 is a plan view of a pitch-board constructed in accordance with my invention. Fig. 2 is a section of the base; Fig. 3, a section of the upright. 25 Figs. 4 and 5 are a side elevation and section of the clamp; Fig. 6, a similar view of the set-screw; and Fig. 7, a cross-section on the line *ff* of the parts, showing the form of slot in which the clamp rides.

30 Like letters of reference indicate like parts in all the figures of the drawings.

1 represents an ordinary square, which is longitudinally slotted, as at *a'a'*.

2 and 5 represent expandable sections of the 35 square 1, and these, like the square, are slotted, as at *a'a'*.

3 and 4 are extensible sections, slotted as at 40 *a'a'*, and connected to the extensions 2 and 5 by set-screws *e*. The sections are all connected to each other by a sliding block, *d*, the sides of which are concaved, as at *d'*, Fig. 5, to fit the convexed edges of the slots, as clearly shown in Fig. 7. The upper half of the sides of the block *d* are narrower than the lower half, so 45 that the same can be introduced into the slots *a'a'* of adjacent sections, and so that when the

screw *c* is tightened the block is drawn upwardly and the head of the screw carried downwardly into contact with the upper side of the upper section, and in this manner 50 the sections are firmly bound in an adjusted position. The length of the block serves to maintain the sections in line with each other. The binding or set screw *e* passes through apertures formed in each of the adjacent sections, 55 and into a washer, *e'*, so that when tightened the sections are firmly secured together, and when loosened the relative position of the adjacent sections may be changed.

Now, the operation of the instrument is as 60 follows: When it is desired to lay off the treads and risers of stairs, the section 5 and the adjacent portion of the square 1 are laid in a position to indicate the tread, and the set-screws *e* and the screws *c* being loosened, the section 65 2 is moved upwardly on the part 1, and this movement causes a movement of the sections 3 and 4 upon each other until the desired height of the riser is indicated by 1 and 2 conjointly, when it will be found that the sections 70 3 and 5 form at their outer edge a straight line conforming to the edge of the plank in which the steps are to be cut. The screws are now tightened, and by successively applying the instrument to the plank the treads and risers 75 can be readily marked and subsequently sawed out. A similar manipulation of the parts adapts the instrument to the laying out of miters of different angles.

Having described my invention and its operation, what I claim is—

The combination of the square 1, having the beveled-edge slots *a'a'*, and the extensions 2'5, having slots *a'a'*, with the sections 43, the former having beveled-edged slot *a'*, and the latter 85 slot *a'*, the thumb-screws *c*, and bar *d*, having beveled sides *d'*, substantially as shown and described.

GEORGE W. OLIVER.
